UNITED STATES PATENT OFFICE.

BRITTON E. BYRD, OF GASTONIA, NORTH CAROLINA, ASSIGNOR TO MILL DEVICES COMPANY, INC., OF GASTONIA, NORTH CAROLINA, A CORPORATION OF NORTH CAROLINA.

KNOTTER.

Application filed June 17, 1927. Serial No. 199,482.

This invention is an improvement in knotters, and more particularly in knotters designed for tying weaver's knots.

In the weaving of textiles, it is frequently necessary to knot broken threads or strands, and in order that the finish of the textile be not marred, it is essential that the knot be of a nature such that it will not stand out noticeably from the finished product.

10 The least noticeable variety of knot is what is known as the weaver's knot, which provides for a small flat nonslipable connection between the broken strands. In my prior Patent No. 1,572,181 of Feb. 9, 1926, a 15 form of mechanism is shown for the mechanical tying of weaver's knots.

In this mechanism, the strands are laid in holders in substantially parallel relation on opposite sides of the tying bill. When the 20 mechanism is put into operation, the threads are first positively crossed, after which the knot is formed and stripped from the bill. One strand, the primary, is cut by the tying bill, while the other, the secondary, is cut 25 by a cutter on the frame, or a fixed blade on the knot stripping device.

In order that the crossing mechanism may function as intended, it is essential that the strands be laid in the holders in the proper 30 manner, that is in substantially parallel relation, or one along side the other, and that each strand be in the appropriate pair of holders. Unless the strands are so laid, the strand crossing mechanism cannot perform 35 its intended function, and the resulting knot is not a weaver's knot, but instead a spooler's knot.

In the tying of strands of silk, rayon, and the like, there is liability to breakage of the 40 fiber from compression of the strand and abrupt bending in the operation of the crossing mechanism. Furthermore, a pure silk strand tends to slip around the tying head if the secondary strand is cut before the 45 formation of the knot, thus preventing the knot formation.

It is also desirable in dealing with any character of thread, but especially with silk and rayon, not only that the secondary 50 strand be cut after the formation of the knot, but that it be cut as close to the knot as possible, in order to eliminate loose ends in the completed fabric.

One of the primary objects of the present

invention is the provision of mechanism to 55 prevent placing of the strands in the guides in any other than the proper manner, thus to eliminate the possibility of inadvertent tying of other than a weaver's knot.

Another object is the provision of strand 60 crossing mechanism especially designed for silk, rayon, and the like, of a nature such that abrupt bends in the strand and undue compression in the crossing mechanism is prevented.

Another object is the provision of cutting mechanism for the secondary strand, so arranged and controlled that it comes into operation at about the time the knot is formed and stripped from the bill.

With these and other objects in view the invention consists in the construction and novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings forming a part hereof:

Fig. 1 is a side view of the improved knotter.

Fig. 2 is a vertical section in the plane of 85 the supporting frame.

Fig. 3 is a view similar to Fig. 2 with parts removed to show the mechanism for holding the knotted strands during the stripping of the knot.

Fig. 4 is a perspective view of the said means and the tying bill at the commencement of the tying operation.

Fig. 5 is a perspective view showing the position of the parts just prior to the stripping of the knot.

Fig. 6 is a similar view just after the knot is stripped.

Fig. 7 is a section on the line 7—7 of Fig. 4.

Fig. 8 is a detail showing the cooperation between the elements for insuring the proper placing of the strands.

In the present embodiment of the invention, the improved knotter comprises a 105 frame composed of side plates 1 and 2, connected by bolts 3, and held in spaced relation by spacing plates 4 and 5, the last

named plate being substantially U-shaped as shown more particularly in Fig. 2.

A thumb lever 6 is pivotally mounted between the plates on a shaft 7, and the lever has integral therewith a cam 8 which operates the tying bill indicated generally at 9. The lever is normally biased to the position of Figures 1 and 2 by a spring not shown, and the frame is provided with a hand encircling grip 10, a part of which is constituted by a leather strap as shown.

Each of the plates 1 and 2 is provided at the end remote from the hand grip with a pair of thread seats or holders, those in connection with the plate 1 being indicated at 11 and 12, while those in connection with the plate 2 are indicated at 13 and 14 respectively. The threads or strands to be tied, indicated at 15 and 16 respectively are laid in the holders, the strand 15 being laid in the holders 11-13, while the strand 16 is laid in the holders 12-14.

The tying bill indicated generally at 17 is of usual construction, having a helical portion 18 which is engaged by an arm 19 bent laterally from the cam 8, the arrangement being such that when the cam lever is swung downwardly toward the hand grip, the arm 19 by its engagement with the helical portion of the bill will rotate the bill through a complete revolution of 360°.

The tying bill includes a pair of fixed jaws 20, and a movable jaw 21, which is a cutting and clamping jaw, moving between the jaws 20, and cutting and clamping one of the strands in a manner to be described. The tying bill extends through the spacing plate 5, and the movable jaw 21 has a cam portion 22, moving in a circular opening 23 in the spacing plate, said opening being eccentric to the axis of the bill, so that rotation of the bill operates the movable jaw to cause it to cut, clamp and release the thread.

The strands are positively crossed, that is they are bodily moved by moving mechanism as contra-distinguished from guided movement, into crossed relation. Referring to the drawings, it will be seen that those portions of the frame plates 1 and 2 which carry the holders 11-12, 13-14, are offset outwardly, and that the jaw portion of the tying bill is between the pairs of holders. The arrangement is such, the bill normally standing with the jaws upright, as indicated in Figures 1 and 2, that when the strands are laid in the holders, they will be on opposite sides of the upstanding portion of the bill, that is on opposite sides of the jaws which are then in register, and one strand, the strand 15 in the present instance, will lie across the body of the bill.

The crossing mechanism includes a pair of rockers 24 and 25, the former being pivoted at 26 on the frame plate 1, while the latter is pivoted at 27 on the frame plate 2.

Each of these rockers is notched as indicated at 28 and 29 respectively. With each rocker is connected the forward end of a slide 30 and 31 respectively, the said slides moving through openings in the connections between the outwardly offset portions of the frame plates and the bodies thereof, to the pivotal connection with the rockers. 70

The principal portion of each slide moves on the outer face of the adjacent frame plate, and these portions are connected by a connecting rod 32 extending across the frame and moving in slots in the frame plates, one of which is indicated at 33. This shaft normally rests in a notch 34 in the cam 8 before mentioned, and when the thumb lever is moved toward the hand frame, the shaft rides up the inner wall of the notch 34 until released therefrom, after which it moves along the arc shaped upper 85 edge 35 of the cam.

The arrangement is such that at the beginning of the movement of the thumb lever the slides are moved forwardly to operate the rockers to cross the threads. As soon as the operation of the crossing is completed, the shaft is released from the cam and no longer is moved thereby, riding upon the edge 35. When the thumb lever is released, the early part of its return movement under the influence of the spring does not effect the shaft, and there is no movement of the shaft until it contacts with the front wall of the notch 34, which is extended to form a nose as shown at 36 for engaging the shaft, to constrain it to move into the notch, and thus return the rockers to normal position. 95

The operation of the rockers, which move only the strand 16, that is the outermost is supplemented by the slides 30 and 31. Each of these slides is provided near its connection with the adjacent rocker, with an outwardly extending finger 37 for the slide 30 and 38 for the slide 31. These fingers overlie the innermost strand, when the parts are in normal position, and are adapted to engage above said strand, to move it outwardly beneath the outermost strand, which at the same time is moved inwardly and downwardly by the rockers. Thus the strands are crossed on the opposite sides of the bill, into the position shown in Fig. 4, the said strands being positively moved into the crossed relation. 110

The relation of the helical portion of the tying bill and the arm 19 is such that when the crossing of the strands is completed, the tying bill has completed a little less than 90° of its travel, that is it is in about the position of Fig. 4. Continued movement of the thumb lever and of the bill causes the point thereof to move between the strands beyond the cross at the left of the bill in Fig. 4, to form the strands into a loop and to cut and 120

clamp one thread, after which the formed loose knot is stripped from the bill, by the stripper mechanism indicated at 39.

This mechanism is in the form of a lever

5 pivoted at 40 between the frame plates. The rear end of the lever extends above the arm 19 of the cam as shown in Fig. 2, and the said end is so curved that the forward movement of the arm 19 does not effect the 10 lever until the arm 19 passes beyond the pivot 40. Then the arm engages a depending finger 41 on the lever and swings the outer or forward end of the lever abruptly upward.

15 The said outer or forward end has a lateral extension 42 normally lying beneath the tying bill and extending across the same, and the free end of the extension has an upward hook 43 which is designed to engage the strands between the tying bill and the seats or holders 13—14 to strip the knot from the bill. After the knot is stripped from the bill the strand 15 is cut between the bill and the seats or holders 11—12, the 20 strand 16 having been previously cut by the cutting and clamping jaw 21 of the bill.

The above described mechanism is substantially that shown and described in my prior patent above mentioned, and in Boyce 30 Patent No. 1,599,160, dated September 7, 1926. With this construction to insure the tying of a weaver's knot, it is essential that the strands be laid in the appropriate holders, the inner strand in the holders 11—13, 35 and the outer strand in the holders 12—14. Through inadvertence, or by intention, the strands may be improperly placed, in which event a spooler's knot will result.

In order to insure the proper placing of 40 the strands, mechanism is provided to prevent the placing of them in any other position than in the appropriate holders. The said mechanism includes an arc shaped arm 44 normally lying transversely of the frame, 45 between the members of the respective pairs of holders. This arm has a stirrup or U-shaped extension 45, which is pivoted on one of the connecting bolts 46 between the side plates.

50 The arms of the stirrup are mounted on the bolt, one between the frame plates, and the other outside the plate 1, and a coil spring 47 arranged on the bolt, normally acts to hold the arm 44 in the position shown 55 in Figures 1 and 2. The arm is in the path of movement of the stripper when it moves upward, and the pivotal mounting enables the stripper to swing the arm so that it does not interfere with the movement of the stripper. As soon as the stripper returns to normal position the spring 47 returns the arm 60 to normal position.

The free end of the arm is just above an upwardly extending finger 48 on the rocker 65 25, which in the normal condition of the

parts is substantially vertical and is slightly within a line dropped from the free end of the arm 44. The arm 44 and the finger 48 effectively prevent placing of the strands in other than the proper holders. The only 70 way in which the strands can be misplaced is to swing one or the other of the strands laterally between the adjacent ends of the arm and finger, and it is obvious that such lateral movement of the strand could only 75 happen by intention, and not through inadvertence.

In tying silk, rayon, and the like, it is desirable to prevent undue compression of the strand, and abrupt bending. With this 80 object in view the inner face of the rocker 25 is provided with a facing 49 of padding material, such for instance as soft leather, this facing being held in place by the pivot 27 of the rocker and an integral clip 50 85 on the rocker, the clip overlying the end of the padding or facing remote from the pivot. The provision of the facing also enables a better gripping action with less pressure, because the co-efficient of friction of 90 the leather is higher than that of metal.

The forward end of the slide 31 which operates the rocker is bent or curved inwardly as shown more particularly at 51 in Fig. 7, to present a rounded surface against the inner strand 15 when moving it into crossed relation. The finger 38 above mentioned is at the top of this curved portion. That portion of the strand which is between the slide and the rocker during crossing is grasped between the padding and the slide with sufficient firmness to enable straining of the knot, but in a manner such as to prevent injury to the strand.

With silk and rayon, the strand 16 should 105 be cut between the bill and the holders 11—12 at about the same time that the knot is formed and stripped, since strands of this character will slip out around the tying head and fail to form a knot, if the 110 said strand is cut before the knot is formed and at least partially tightened.

With this object in view, the cutter for the strand 16 at the point specified is mounted on the stripping device, and is operated by 115 the movement of the stripper in stripping the knot. The cutting mechanism includes an elbow lever, one arm of which indicated at 52 is a blade, cooperating with a fixed blade 53 secured to the stripping device. Referring 120 to Fig. 5, it will be seen that the blade 53 is in the form of an angle plate, one arm of which is secured to the part 42 of the stripper, the other arm forming the blade, and being secured to the body of the stripper in 125 spaced relation. The elbow lever is pivoted between this fixed blade and the body of the stripper.

The other arm 54 of the elbow lever has a hook, which engages in a slotted extension 130

- 55 on an arm 56 which has a stirrup 57 pivoted on one of the connecting bolts 59 between the side plates. The operation of the parts just described is as follows. When the 5 parts are in normal position the blade 52 is open as shown more particularly in Fig. 2. At the beginning of the upward movement of the stripper, the hook of the elbow lever arm 54 moves freely in the slotted extension. 10 As the movable blade nears the level of the tying bill jaws, which at this time are substantially vertical, the blade begins to move toward the fixed blade and the cutting movement is completed as the stripper reaches 15 the end of its upward movement. At this time the knot is completely formed and substantially tight.

During the straining operation the strands are held on one side of the bill by the holders 20 13—14, and at the other side by the clamping jaw of the tying bill, and by the holder 12. The cutter for the strand 15 between the bill and the holder 12 operates to cut at about the moment when the knot begins to strip 25 from the tying bill.

The operation of the knotter is as follows. The strands 15 and 16 are laid in the holders 11—12, 13—14, and because of the elements 30 44 and 48, they must be properly laid. As the thumb lever is depressed, the strands are crossed on each side of the tying bill by the rockers and slides. There are no abrupt bends and no crushing and chafing between opposing rigid surfaces when dealing 35 with silk and rayon. As the crossing is completed, the tying bill comes into operation, forming a knot in the strands, and cutting and clamping the strand 16 between the bill and the holders 11—12.

- 40 After the knot is formed, the stripper comes into operation and strips it from the tying bill. At the moment when the knot is complete, and substantially strained, the cutter for the strand 15 comes into operation. 45 The stripper in stripping the tied strands from the bill engages what may be considered as the loop formed by the tying of the strands, as clearly shown in Fig. 6. The strands are at this time held by the holders 50 13—14, so that the knot is thoroughly tightened before the strands are released by the holders.

What is claimed as new is:—

1. In a knotter including a tying bill and 55 a pair of holders at each side of the bill for holding a plurality of strands in substantially parallel relation on opposite sides of the bill, and means to separate the strands and to guide each strand into the appropriate set of holders.
2. In a knotter including a frame, a tying bill, and a pair of holders in connection with the frame at each side of the bill for holding a plurality of strands in substantially parallel relation on opposite sides of the bill, 65 rockers for engaging the outermost strand, slides for operating the rockers having

the bill, and means to separate the strands and to guide each strand into the appropriate set of holders, said means including an arm extending from the frame between the members of one pair to a point near the 70 opposite pair and between the members thereof.

3. In a knotter including a frame, a tying bill, and a pair of holders in connection with the frame at each side of the bill for 75 holding a plurality of strands in substantially parallel relation on opposite sides of the bill, and means to separate the strands and to guide each strand into the appropriate set of holders, said means including 80 an arm extending from the frame between the members of one pair to a point near the opposite pair and between the members thereof, and means in connection with the frame between said opposite pair for co-operating with the arm.

4. In a knotter including a frame, a tying bill, a pair of holders at each side of the bill for holding a plurality of strands in substantially parallel relation on opposite 90 sides of the bill, and a stripper for the formed knot movable bodily with respect to the bill and the holders, and means to separate the strands and to guide each strand into the appropriate set of holders, said 95 means including an arm extending from the frame between the holders of one pair to near the frame at a point between the members of the other pair, said arm in the path of movement of the stripper and pivotally mounted to be swung out of position by the stripper in its stripping movement, and a spring for holding the arm in normal position.

5. In a knotter having knot forming 105 means, and stripping means movable with respect thereto to strip and strain the formed knot, means for clamping the strands to provide counter pressure for the stripping and straining means, said clamping 110 means having an engaging surface thereof faced with material having a high co-efficient of friction.

6. In a knotter having knot forming means, and stripping means movable with 115 respect thereto to strip and strain the formed knot, means for clamping the strands to provide counter pressure for the stripping and straining means, said clamping 120 means having an engaging surface thereof faced with material having a high co-efficient of friction, said means shaped to prevent abrupt bends in the strand.

7. A knotter comprising a tying bill, and means to cross the strands on each side of 125 the bill, said means including holders for supporting the strands in substantially parallel relation on opposite sides of the bill, rockers for engaging the outermost strand, slides for operating the rockers having 130

- means to engage the innermost strand and move it above the outermost strand, the strand engaging face of the rocker at one side of the bill provided with a facing of 5 relatively soft material having a high coefficient of friction and the engaging edge of the adjacent slide curved to prevent abrupt bending of the strand.
8. In a knotter including a supporting frame, a tying bill journaled therein, a pair of holders in connection with the frame at each side of the bill for supporting a pair of strands in substantially parallel relation on opposite sides of the bill, and means to 10 cross the strands on opposite sides of the bill, said means cooperating with the frame to grip the strands at the holders at one side of the bill, the strand engaging surfaces of one of said elements padded to prevent crushing of the strands.
9. In a knotter including a supporting frame, a tying bill journaled therein, a pair of holders in connection with the frame at each side of the bill for supporting a pair 15 of strands in substantially parallel relation on opposite sides of the bill, and means to cross the strands on opposite sides of the bill, said means cooperating with the frame to grip the strands at the holders at one side of the bill, the strand engaging surfaces of one of said elements padded to prevent crushing of the strands, and the engaging edges thereof convex.
10. In a knotter including a tying bill, 20 means to support a pair of strands in substantially parallel relation on opposite sides of the bill, means to cross the strands, and means to strip the knotter from the bill,
- means carried by the stripping means to sever one of the strands near the end of 40 the stripping movement, said means operated to cut by the stripping movement of the bill.
11. In a knotter including a tying bill, means to support a pair of strands in substantially parallel relation on opposite sides 45 of the bill, means to cross the strands, and means to strip the knot from the bill, means carried by the stripping means to sever one of the strands near the end of the stripping movement, said means including a fixed blade on the stripping means, a movable blade pivoted thereto, and a lost motion connection between the movable blade and the frame for operating the blade to cut near 50 the end of the movement of the stripping means.
12. In a knotter including a tying bill, means to support a pair of strands in substantially parallel relation on opposite sides 55 of the bill, means to cross the strands, and means to strip the knot from the bill, means carried by the stripping means to sever one of the strands near the end of the stripping movement, said means operated to cut by 60 the stripping movement of the bill, and means cooperating with the strand supporting means at one side of the bill to make counter pressure against the stripping means, said cooperating means padded and 65 shaped to prevent abrupt bends in the strands.

Signed at Gastonia, in the county of Gaston and State of North Carolina, this 11th day of June A. D. 1927.

BRITTON E. BYRD.
